CLAIM

The ornamental design for a footwear upper, as shown and described.

DESCRIPTION

FIG. 1 is a front perspective view of the footwear upper; FIG. 2 is a top view thereof; FIG. 3 is a left side view thereof; FIG. 4 is a right view thereof; FIG. 5 is a front view thereof; and, FIG. 6 is a rear view thereof.

The dot-dot-dash broken lines in the figures show features of an article of footwear that form no part of the claimed design. Further, the dot-dot-dash broken lines immediately adjacent the portions shown in solid lines form the boundary of the design, with the broken lines forming no part of the
